UNITED STATES PATENT OFFICE

WALTER H. COTTON, OF CHICAGO, ILLINOIS, ASSIGNOR TO UNION DRAFT GEAR COMPANY, OF CHICAGO, ILLINOIS, A CORPORATION OF DELAWARE

DRAFT GEAR

Application filed March 23, 1925. Serial No. 17,611.

This invention relates to shock absorbing devices and more especially to draft gears of the friction type for use on railway cars and the like.

6 One of the objects of the invention is the provision of a draft gear provided with new and improved friction means for assisting in resisting the inward movement of the friction shoes during the compression of the gear.

10 A further object of the invention is the provision of new and improved means for insuring substantially the same amount of pressure on the friction elements at each end of the gear, during the compression of the same.

15 Another object of the invention is the provision of a new and improved arrangement of friction plates and cooperating springs and wedge members.

20 Other and further objects and advantages of the invention will appear from the following description taken in connection with the accompanying drawings, in which

25 Fig. 1 is a plan view of a draft gear showing the same in position, with parts broken away and parts in section;

Fig. 2 is a section on line 2—2 of Fig. 1;

Fig. 3 is a view similar to that shown in Fig. 1 but with parts in compressed position;

30 Fig. 4 is a perspective view of one of the friction plates;

Fig. 5 is a perspective view of one of the friction or drag plates;

Fig. 6 is a perspective view of the friction shoe or wedge member;

Fig. 7 is an end elevation of one of the follower members; and

Fig. 8 is a side view thereof.

40 On the drawings the reference characters 10 and 11 designate center sills of a railway car, each of which is provided with a draft lug 12 and a buffer lug 13. The draft gear 14 is mounted between the lugs 12 and 13 and 45 is embraced by the draft yoke 15 secured to

the draw bar 16 as is usual in such constructions.

The draft gear 14 includes a pair of follower members each of which comprises a casing 17 and a follower block 18. The follower block 18 may be and preferably is made integral with the casing although it is understood that it may be a separate and independent block.

Each casing 17 is provided at each side 55 thereof with a lug or shoulder 170 having an inclined surface 19 on its inner portion, and a spring seat or socket 21 on its outer portion. The outer sides of the casings 17 are cut away as shown at 22 in Fig. 8 to permit the spring sockets 21 to be placed farther apart, thereby increasing the space for the reception of the friction plates as will presently appear.

60 The casings 17 are provided with friction elements for resisting the inward or compressing movement of the gear. In order to simplify the construction and reduce the number of parts of a draft gear of the friction type, a single group of friction plates are 65 employed. This group comprises the two sets of friction plates 23 and 24 overlapping at their inner ends. The plates are all alike, and each is provided with an elongated opening 70 for receiving the corresponding retracting 75 bar 25 and a slot 30 in its inner end for receiving the opposite retracting bar 25.

75 Means are provided for creating lateral pressure on the plates during the compression of the gear. This means comprises a pair of 80 wedging members or shoes 26, one at each side of the friction plates. The shoes are each provided with inclined surfaces 27, see Fig. 6, which are adapted to engage the corresponding inclined surfaces 19 on the lug or 85 shoulder 18 and with a spring seat or socket 28 at each side of said surface.

85 Springs 29 are provided for engaging the seats 28 of the wedging members or shoes 26. The springs 29 are arranged in pairs at the 90

upper and lower sides of the gear, the same being above and below the wedging surface 27 whereby the springs will prevent the wedge from turning or twisting during the 5 operation of the gear. These springs resist the inward movement of the wedges during compression of the gear, thereby causing the latter to press laterally inwardly on the friction plates for cushioning or absorbing shocks 10 and the like.

Springs 31 are seated in the sockets 21 in the casings 17 for releasing the lateral pressure on the friction plates after compression.

It is desirable that means be provided for 15 assisting the springs 29 in resisting the inward movement of the shoes 26 during the initial compression of the gear. In the form of the device selected to illustrate one embodiment of this feature of the invention, 20 suitable friction members are employed for this purpose. As shown, friction plates 32, which for convenience of description will be termed drag plates, are inserted in the group of friction plates, preferably, although not necessarily along the median line of said 25 group. Each plate 32 is provided with an opening 33 for the reception of the corresponding retracting bar 25, which makes a close fit therewith. The slots 20 of each friction plate 23 being elongated permits a relative movement between the plates and the retracting bars during the initial compression of the gear.

The drag plates 32 are also employed as 35 means for equalizing the friction as between the two ends of the draft gear during the compression of said gear. It is evident from an inspection of Fig. 1 that on compression of the gear, especially after the follower 40 members 18 engage the frictional plates 23, there is relative movement between said plates and the wedging members or shoes. Since the plates 23 engage the wedging members or shoes at each end of the gear, it is evident 45 that the frictional resistance between the shoes and the plates will tend to loosen the wedge members or shoes at the left of Fig. 1 and tighten those at the right, inasmuch as the frictional resistance between the plates 50 23 and the shoes will tend to carry the shoes along with the plates. The drag plates 32 being located between two of the friction plates 24 will tend to move with the plates as they are moved toward the left in Fig. 1. By 55 means of this arrangement the tendency of the plates 23 to move the wedge members or shoes 26 to the right in Fig. 1 during the collapsing of the gear is counteracted or compensated for by the tendency of the 60 plates 24, through the drag plates 32 and retracting bars 25, to move the wedge members or friction shoes 26 toward the left in said figure. As a result, the wedging members or 65 shoes 26 are caused to exert substantially the same force laterally on each end of the gear,

and consequently after compression the pressure at each end of the gear will be simultaneously released, thereby insuring a prompt return of the parts to normal position.

I claim as my invention:—

1. In a draft gear, a pair of follower members, intercalated friction plates between said followers, means including friction shoes for causing inward lateral pressure on said plates during compression of said gear, 70 springs engaging said follower members for resisting inward movement thereof, said shoes each being provided with a wedging face and a spring socket at each side of said face, and a plurality of springs seated in said sockets for resisting the inward movement of said shoes.

2. In a draft gear, a pair of follower members, a group of intercalated friction plates between said followers, means including 85 wedging friction shoes for creating lateral pressure on said plates during compression of said gear, and means including drag plates movable relatively to all of said friction plates for resisting the inward movement of 90 said shoes during the initial compression of the gear.

3. A draft gear comprising a pair of follower casings, a single group of friction plates within said casings, means at the outer 95 ends of said casings for engaging the ends of said plates, means comprising wedging friction shoes and cooperating friction surfaces on said followers for producing lateral pressure on said plates during compression 100 of said gear, means engaging said followers for returning the same to normal position after compression, and means including a plurality of springs engaging each of said 105 shoes for returning said shoes and plates to normal position after compression.

4. In a draft gear, a pair of follower members, intercalated friction plates between said followers, means including friction shoes for creating lateral pressure on said plates during compression of said gear, and means including drag plates movable with said shoes and movable relatively to said friction plates during the initial compression of the gear for resisting the inward movement of said shoes. 110

5. In a draft gear, a pair of followers, each provided with an inclined surface and with spring seats at each side thereof, intercalated friction plates between said followers, wedge plates each having an inclined surface for 115 engaging the inclined surfaces on said followers, spring seats on said wedge plates, and springs engaging said seats.

6. In a draft gear for a railway car, a wedge shoe having its inner surface plane on its inner face for engaging friction plates and having an inclined wedging surface on its outer face and a spring seat at each side of said wedging surface. 125

7. A draft gear comprising a pair of 130

chambered followers each having an inclined wedging surface facing inwardly at each side thereof, a spring seat adjacent to said surface, a group of intercalated friction plates within said followers and movable relative to said followers, wedging shoes for engaging said inclined surface and said plates and provided with spring seats, springs engaging said seats, retracting bars for returning the parts to normal position after compression and drag plates secured to said bars and engaging said friction plates for equalizing the resistance to the inward movement of the shoes at each end of the gear.

In testimony whereof I affix my signature.

WALTER H. COTTON.
